UNITED STATES PATENT OFFICE

JAMES S. THOMPSON, OF NEW ROCHELLE, NEW YORK, ASSIGNOR TO FIREBAR CORPORATION, OF CLEVELAND, OHIO, A CORPORATION OF DELAWARE

GRATE BAR

Application filed March 28, 1930. Serial No. 439,685.

This invention relates to grates of the type used in locomotives, marine boiler furnaces and for other heavy duty purposes. More specifically, the invention is concerned with a grate bar which contains numerous features of novelty by virtue of which the bar makes possible better distribution of air to the fuel, resulting in increased combustion efficiency, higher fire box temperatures, absence of clinkering, etc. The new grate bar is also constructed in such manner that its weight is substantially lower than bars of present standard construction used under the same conditions. The advantages of the new bar are not confined to any particular use but it will be described in an adaptation suitable for use in locomotives, with the understanding that such form is merely illustrative.

With the increasingly heavy demands that have been made on motive power by railroads in the last few years, locomotives have increased in size and weight and the latter has been added to by the installation of such appliances, as feed water heaters, superheaters, etc. The efficiency of the boiler has been improved by this additional equipment, but the fundamental problem of burning the fuel has not received a proportionate amount of attention. As a consequence, while the utilization and conservation of the heat units liberated by combustion have been placed on a more efficient basis, no improvements of considerable importance in the mechanism for burning the fuel have been developed.

The grates now used in locomotives are not substantially different from those which were in use many years ago, but as larger locomotives have been built, the grates have been made correspondingly larger. This increase in size of the grates has resulted in the use of larger and heavier grate bars and grate frames, until in some instances, the limit of weight of the locomotive imposed by the strength of bridges, road bed, etc. has been closely approached.

Grate bars have heretofore ordinarily been made of cast iron and in an attempt to cut down the weight of the grate, some railroads have begun to employ steel grate bars

and frames. Such grates, while satisfactory so far as weight is concerned, are objectionable otherwise because of the tendency of the bars in service to sag and bend out of shape under the load of the fuel. The original 55 cost of steel bars is considerably higher than that of cast iron and the upkeep expense is much greater, not only because of actual cost of replacement parts but also because of the labor charges involved and the loss of service time of the locomotive.

The present invention is accordingly directed to the provision of a grate bar which affords better combustion than bars now in common use and which is much lighter in 65 weight per unit of surface area. This new bar includes removable fuel-supporting units which are ventilated in such manner that burning out is prevented, since the bar is thoroughly cooled in all parts during operation, the ventilation being achieved coincident with the lightening of the weight. The bar includes numerous other features of novelty which will be readily apparent in the detailed description to follow.

For a better understanding of the invention, reference may be had to the accompanying drawing, in which

Fig. 1 is a transverse sectional view of the new grate bar;

Fig. 2 is a fragmentary plan view of a portion of the new bar;

Fig. 3 is a sectional view of the fuel-supporting unit on the line 3-3 of Fig. 1, and

Fig. 4 is a view in side elevation of a portion of the bar.

The bar comprises a carrier member which includes a longitudinal web 10 having a strengthening rib 11 extending downward from its under surface, and a flange 12 extending lengthwise of the web along the top thereof. At each end the carrier member has an upward flange 13 from which projects the usual trunnion 14.

Mounted on the carrier member are fuel-supporting units 15, each of which comprises a plate 16 from opposite faces of which project lugs 17. The lugs are spaced apart to define air channels 18 between them and the chan-

nels extend from the outer face 19 of each lug to the face of the plate 16.

The lugs are hollow and a pair of lugs in registry on opposite sides of the plate 16 together form a box-like structure, the bottom 5 of which is open. The plate 16 extends across the open bottom of this box, as illustrated more clearly in Fig. 3 and air may enter the structure from below through the opening 20. Preferably the end of each lug is formed with 10 a passage 21 extending from top to bottom thereof, this passage sub-dividing the lug into two parts permitting the flow of air upwardly to the fuel supported on the unit. Through the top of each unit is formed an air exit 15 opening 22 which leads from the interior of the box to the upper surface thereof and provides for the flow of air upwardly from the interior of the box to fuel carried thereby.

In order to afford a better distribution of 20 the air and thereby to bring about a more efficient combustion of the fuel, the fuel-supporting surface of the unit may be sub-divided into a plurality of small fuel-supporting areas. The latter may conveniently be 25 formed by providing the top of each lug and the top of the plate 16 with upwardly extending projections 23 separated by intersecting air channels 24 and 25. In the construction 30 illustrated, each part of each lug carries a group of four projections 23 and a pair of another group 26, two projections of the group 26 lying above the lug and the other projections of this group lying above the plate. The 35 projections of the outer group on the half lug and the projections of the inner group are separated by an air channel 27 of some-what greater width than the channels 24 and 25. Channels 25 communicate with the pas- 40 sage 19 between the two parts of the lug and with a passage 18, between adjacent lugs. The channel 27 communicates with similar 45 passages. Along the top of the plate 16 is an air channel 28 into which the exit opening 22 leads. With the arrangement described, it 50 will be seen that the fuel-supporting surface of the unit, which is made up of the tops of the lugs and the top of the plate, is sub-di- 55 vided by the various air channels into a mul- tinity of small areas, each of which is cooled by air flowing on all sides thereof. The fuel on the areas is thus in contact with only a small amount of dead surface and the fuel is thus burned more effectively than is 60 possible with grate bars in which the air openings are of large size and are separated by solid portions of the bar of substantial width.

By constructing the lugs in the form of 65 hollow boxes, the bar is made lighter in weight and at the same time the metal is maintained cool and burning out is thus pre- 70 vented. Also, air which flows up through the boxes reaches the fuel lying above the 75 middle of the unit and more effective com-

bustion is thus obtained. It has been found in practice that in a bar of this construction in which the fuel-supporting surface is sub- 70 divided into many small areas, the fuel is consumed into fine ash and by forming the air channels so that their bottom surfaces slope downwardly and outwardly, as indicated at 29 in Fig. 3, the ash may slide down through the air channels to the air passages and thence fall into the ash pan. 75

In the bar illustrated, the units are mounted loosely on the carrier member, each unit having a recess 30 formed in the plate, the shape of this recess corresponding generally to the cross-section of the carrier member. 80 At the mouth of each recess, there are inwardly extending lugs 31, the distance between which is only slightly greater than the overall width of the carrier member. The recess 30 is shaped to receive the flange 12 85 freely and the plate rests on the surfaces 32 of the carrier member on each side of the flange. The carrier member is provided with the usual shaker arm 33 and when the member is shaken, the weight of the fuel on the fuel- 90 supporting units tends to maintain them stationary, the carrier member rocking about one or the other of the points 34 as a pivot. For example, when the carrier member is 95 rocked by movement of the shaker arm to the left (Fig. 1), the carrier member rocks about the left-hand pivot point 34. The surface 32 of the web at the right-hand end of the latter moves away from the wall of the recess in the plate 16. When the carrier 100 member is rocked back, the right-hand sup- 105 porting surface 32 strikes the corresponding wall of the recess in the plate a sharp blow and this jar has a tendency to shake the finely divided ash free from the fuel bed. In 110 use, the grate may be kept clean without any substantial shaking of the bars, a slight movement of each carrier member back and forth serving to jar the fuel-supporting units to the extent sufficient to free the ash from the 115 fuel bed.

Since the lugs 31 are spaced apart a distance slightly greater than the overall width of the web, the fuel-supporting units may 120 be placed on the carrier member by a verti- 125 cal movement and as readily removed there- 130 from should occasion arise. The lugs, how- 135 ever, serve as a locking means for keeping the units from displacement from the car- 140 rier member, since relative movement of the carrier member and unit causes one or the other of the lugs to pass beneath the ad- 145 jacent end of the web of the carrier member, thus preventing dislodgment of the unit from the member.

In installing the new bar, the carrier mem- 150 ber is first inserted in the grate frame in the ordinary manner and thereafter the units are placed in position on it. These units, while resting loosely in position, are kept sepa- 155

rated the proper distance by means of spacing projections 35 formed on the outer ends of certain of the lugs 17.

While the fuel-supporting units are illustrated as removable from the carrier bar, it will be evident that they may be made integral with the carrier bar, or locking arrangements other than those described may be employed.

The new bar may be made of cast iron or of steel as may be desired. In either instance, the bar is substantially lighter than a bar of standard construction made of similar material, by reason of the lugs being hollow and of the formation of the numerous air channels and air passages through the bar. The ventilation of the bar provided by the various passages and channels for air insures that all parts of the bar will be kept cool in operation and at the same time provides a better distribution of air resulting in more efficient combustion.

What I claim is:

1. A grate bar which comprises a carrier member, and fuel-supporting units extending beyond the side edges of said member, each unit comprising a plate, a plurality of spaced lugs projecting from the faces of said plate near the top thereof, each lug being hollow and having an open bottom, opposed lugs on opposite faces of said plate lying in registry and having their hollow interiors in communication.

2. A grate bar which comprises a carrier member, and fuel-supporting units extending beyond the side edges of said member, each unit comprising a plate, a plurality of spaced lugs projecting from the faces of said plate near the top thereof, each lug being hollow and having an open bottom, opposed lugs on opposite faces of said plate lying in registry and having their hollow interiors in communication, and air passages leading upwardly from the interiors of said lugs.

3. A grate bar which comprises a carrier member, and fuel-supporting units each extending beyond both the side edges of said member, each unit comprising a plate, a row of spaced lugs projecting from each face of said plate, the lugs of the two rows lying in registry, the lugs between them defining air passages for upward flow of air and each lug having an air passage leading from bottom to top thereof formed in its outer face.

4. A grate bar which comprises a carrier member, and fuel-supporting units each extending beyond both the side edges of said member, each unit comprising a plate, a row of spaced lugs projecting from one face of said plate, said lugs being hollow and open at the bottom, adjacent lugs defining passages for upward flow of air and each lug having a similar passage formed in its outer face, and a multiplicity of fuel-supporting projections

lying above said lugs, said projections being separated by air channels.

5. A grate bar which comprises a carrier member, and fuel-supporting units each extending beyond both the side edges of said member, each unit comprising a plate, a row of spaced lugs projecting from at least one face of said plate, adjacent lugs defining passages for the upward flow of air between them and each lug having an air passage formed in its outer face.

6. A grate bar which comprises a carrier member, and fuel-supporting units each extending beyond both the side edges of said member, each unit comprising a plate, and a row of spaced lugs extending from at least one face of said plate, adjacent lugs defining between them a passage for upward flow of air and each lug being formed with a similar passage in its outer face, each lug being hollow and open at the bottom and having an air exit opening at the top.

7. A grate bar which comprises a carrier member, and fuel-supporting units each extending beyond both the side edges of said member, each unit comprising a plate having a row of spaced lugs extending from at least one face thereof near the top, each lug having its upper surface sub-divided by horizontal air channels into a plurality of small fuel-supporting surfaces, the outer face of each lug being formed with a passage for upward flow of air, said passage communicating with certain of said channels and adjacent lugs defining between them a passage for upward flow of air, said passage being in communication with certain of said channels.

8. In a grate bar, a fuel-supporting unit which comprises a plate, a row of spaced lugs projecting from said plate along one face thereof, adjacent lugs between them defining a passage for upward flow of air, each lug being hollow and having an opening at its lower end for intake of air and a top opening for outlet of air, each lug being formed with an air passage in its outer face.

9. In a grate bar, a fuel-supporting unit, which comprises a plate, a row of spaced lugs projecting from one face of the plate near the upper edge thereof, adjacent lugs between them defining a passage for upward flow of air, each lug having a similar passage in its outer face.

10. In a grate bar, a fuel-supporting unit comprising a plate, a row of spaced lugs projecting from one face of the plate, each lug being hollow and having an open bottom, a second row of spaced lugs projecting from the other face of the plate, the lugs of said second row being hollow and having an open bottom, the lugs of the two rows being in registry and registering lugs having their hollow portions in communication, said plate having air exit openings between registering

lugs communicating with the hollow interiors thereof.

11. In a grate bar, a fuel-supporting unit comprising a plate, a row of spaced lugs projecting from one face of said plate, each lug being hollow and having an open bottom in communicating with an air exit opening formed in the top of said plate, and a plurality of fuel-supporting projections extending upwardly above said lugs and separated by air channels.

12. In a grate bar, a fuel-supporting unit which comprises a plate, a row of spaced lugs projecting from one face of the said plate, and a row of spaced lugs projecting from the other face of said plate, the lugs of the two rows being in registry, each lug being hollow and having an open bottom, the hollow interiors of opposed lugs being in communication, said plate having air exit openings each of which communicates with the hollow interiors of a pair of opposed lugs, adjacent lugs defining an air passage between them and each lug having an air passage formed in its free end, and a plurality of fuel-supporting projections lying above said lugs and separated by air channels communicating with said passages.

In testimony whereof I affix my signature.
